(57) **CLAIM**

The ornamental design for an autosampler carousel assembly, as shown and described.

DESCRIPTION

FIG. 1 is a top and side perspective view of an autosampler carousel assembly showing my design;

FIG. 2 is a top view thereof;

FIG. 3 is a bottom view thereof;

FIG. 4 is a side view thereof;

FIG. 5 is an opposing side view thereof;

FIG. 6 is front view thereof;

FIG. 7 is a back view thereof;

FIG. 8 is a top, side perspective environmental view thereof in a state of use;

FIG. 9 is a top view of the autosampler carousel assembly showing a portion of the tiered sample carrier, the central sample carrier is removed to disclose details of the article not otherwise discernable from the assembled autosampler carousel assembly;

FIG. 10 is a bottom view thereof;

FIG. 11 is a side view thereof;

FIG. 12 is an opposing side view thereof;

FIG. 13 is front view thereof;

FIG. 14 is a back view thereof;

FIG. 15 is a side perspective view thereof;

FIG. 16 is a top view of the autosampler carousel assembly showing the central sample carrier, the tiered sample carrier is removed to disclose details of the article not otherwise discernable from the assembled autosampler carousel assembly;

FIG. 17 is a top view thereof;

FIG. 18 is a bottom view thereof;

FIG. 19 is a side view thereof;

FIG. 20 is an opposing side view thereof;

FIG. 21 is a front view thereof; and,

FIG. 22 is a back view thereof.

The dashed lines shown in FIGS. 1-7 and 9-22 depict portions of the auto sampler carousel assembly that form no part of the claimed design. The additional dashed lines shown in FIG. 8 depict environmental subject matter and

(Continued)

form no part of the claimed design. The dot dash broken lines depict boundaries of the enlarged views and form no part of the claimed design.
